UNITED STATES PATENT OFFICE.

PETER CARLSON, OF DOVER, MINNESOTA, ASSIGNOR OF ONE-FOURTH TO IRVING J. RICE, OF ST. PAUL, MINNESOTA.

DRIP CATCHER.

1,410,889.

Specification of Letters Patent. Patented Mar. 28, 1922.

Application filed August 9, 1920. Serial No. 402,392.

To all whom it may concern:

Be it known that I, PETER CARLSON, residing at Dover, in the county of Olmsted and State of Minnesota, have invented certain new and useful Improvements in Drip Catchers, of which the following is a specification.

This invention relates to improvements in drip catchers for liquid containers and its object primarily is to provide a liquid container with pouring means that will not drip and waste the liquid after each pouring operation. While it is adapted particularly for use as a syrup container it can be used for other liquids or semi-liquids. My drip catcher can be made integral with the container as in the case of syrup pitchers, or it can be made separately and in standard sizes to fit glasses, mugs etc. that are made in such sizes. With the foregoing and other objects in view the invention consists in the combination and arrangement of parts to be hereinafter fully described, pointed out in the appended claims and illustrated in the accompanying drawing which forms a part of this specification and in which—

Fig. 1 is a fragmentary sectional view of a liquid container embodying my improved drip catcher.

Fig. 2 is a top plan view of the same with the top open.

Like reference characters denote corresponding parts in both views.

The reference numeral 1 denotes the body of the container which may be formed with my improved drip catcher attachment or to which the same may be applied. My drip catcher comprises the neck portion 2, annular in this instance, adapted to fit snugly inside the mouth of the container body 1. The neck portion 2, when used as an attachment for containers of standard size such as various drinking glasses, standard jars and the like, is made in standard sizes and preferably of spring metal so that it can be forced into close fitting engagement with the body 1. The neck portion 2 is formed with a flange 3 which projects over the upper edge or mouth of the container body 1 and to said flange, or to the neck portion, the cover or top 4 is hinged. To the flange 3 I secure the pouring spout 5 by the pins 6, the lower edge of said spout being secured to or fitting closely against the neck portion

2 a distance substantially below the rim 3, 55 said spout extending inwardly from its point of contact with said portion 2 and then extending upwardly a substantial distance above the rim 3 and terminating in the mouth portion 7, the body portion of the 60 spout being spaced inwardly from the neck 2 to afford substantial clearance, or form a trough, for drippings from the mouth 7.

In vertical alinement with the pit, or longitudinal center, of the mouth 7 of the 65 spout a perforation 8 is formed in the spout which is of a size to snugly receive a swinging ball 9 supported by a link 10 from a hook 11 which is secured to the inner face of the spout immediately above the perforation 70 8. When the container 1 is tipped or inclined by its handle 12 to cause the liquid contents to flow out through the spout the swinging ball 9, through gravity, seats in the perforation 8 and prevents the liquid, or any portion thereof, from passing out through the same. When the pouring operation is completed and the container disposed in upright position the swinging ball is moved, again by gravity, out of the perforation 8 and 75 suspended within the container. Such liquid as may drip from the spout over the outer surface of the same will flow into the trough formed between the spout and neck 2 and gravitate through the perforation 8 back 80 into the container. This prevents the liquid from trickling down the outside of the container and being wasted or giving the same an unsanitary appearance. The top 4, when closed, completely obscures the spout 5 and 85 90 rests upon the flange 3. The spout is raised to open position by pressure upon the finger piece 13 integral with the top 4 and fulcrumed upon the hinge of said top.

What is claimed is:

1. In combination with a container, a neck fitting snugly into the mouth of the container, a flange formed upon said neck and extending over the mouth of the container, a spout carried by said neck and rising from substantially the lower inner edge of said neck above the said flange, the body portion of said spout being spaced away from the said neck, said spout being formed with a perforation, a swinging ball normally suspended from the inner face of said spout and adapted when the container is tilted forward to seat in the said perforation, and a top

hinged to said neck and adapted in closed position to rest upon said flange completely, covering said spout.

2. In combination with a container, a neck fitting snugly into the mouth of the container, an external flange formed upon said neck and extending over the upper edge of the container, a spout rising from the lower edge of said neck and forming a trough therewith, said spout being formed with a

perforation registering with said trough adjacent its lowest point, a gravity controlled

closure for said perforation operative when the container is inclined in one direction, and a top hinged to said neck and adapted in closed position to rest upon said flange.

In testimony that I claim the foregoing as my own I have hereto affixed my signature in the presence of two subscribing witnesses.

PETER CARLSON.
